(57) **CLAIM**

The ornamental design for a bottle assembly, as shown and described.

DESCRIPTION

FIG. 1 is a perspective view of the bottle assembly showing the new design in a coupled state, in which the bottle and cap are attached;

FIG. 2 is a top plan view thereof;

FIG. 3 is a bottom plan view thereof;

FIG. 4 is a side elevation view thereof;

FIG. 5 is a perspective view of the bottle assembly in a separated state, in which the bottle and cap are detached, showing the cap upright;

FIG. 6 is a top plan view of the bottle assembly in a separated state, in which the bottle and cap are detached, showing the cap upside down; and,

FIG. 7 is a perspective view thereof.
